(57) **CLAIM**

The ornamental design for a magnetic filter, as shown and described.

DESCRIPTION

FIG. 1 is a front elevation view of a magnetic filter showing my new design;

FIG. 2 is a back elevation view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a bottom perspective view thereof;

FIG. 8 is top perspective view thereof;

FIG. 9 is an enlarged view of the encircled portion labeled “9” in FIG. 7;

FIG. 10 is an exploded view thereof;

FIG. 11 is an enlarged view of the encircled portion labeled “11” in FIG. 1; and,

FIG. 12 is an enlarged view of the encircled portion labeled “12” in FIG. 1.

The dashed-dot lines form the boundary of the enlarged portion view of FIG. 9 in FIGS. 7 and 9 and form no part of the claimed design. The even dashed broken lines shown in the drawings are included for the purpose of illustrating portions of the magnetic filter that form no part of the claimed design.
